UNITED STATES PATENT OFFICE.

OLIVER M. CAMPBELL, OF KANSAS CITY, KANSAS.

VACUUM WATER-PURIFICATION SYSTEM.

1,276,871.

Specification of Letters Patent. Patented Aug. 27, 1918.

Application filed January 27, 1916. Serial No. 74,603.

To all whom it may concern:

Be it known that I, OLIVER M. CAMPBELL, a citizen of the United States, residing at Kansas City, in the county of Wyandotte, 5 State of Kansas, have invented certain new and useful Improvements in Vacuum Water-Purification Systems, of which the following is a full and exact specification.

The present invention relates to water 10 purification systems, and more particularly to water purifying apparatus for use in ice plants deriving their water supply from sources necessitating distilling or otherwise purifying the water to render it fit for ice manufacture; and the general object in view 15 is to devise a novel and improved construction and arrangement of apparatus for effectively and economically purifying water from sources of this character.

20 In carrying out the invention, means is provided for vaporizing the water in the boiler from which the steam is conducted to a condenser; this condenser is provided with suitable vacuum connections 25 for the purpose both of removing impure vapors and of carrying the steam vapor on through additional condensing means into a reservoir. The vacuum connections are such as to exert this double influence on the 30 steam vapor throughout its course; and, furthermore, the vacuum column is arranged in communication with the boiler whereby a balanced effect is maintained upon opposite sides of the condensing and storing apparatus.

With this general object in view, the invention will now be described with reference to the accompanying drawing, forming a part of this specification and illustrating a 40 system which has been devised for embodying the present improvements, after which those features and combinations deemed to be novel will be specified in the appended claims.

45 In the drawing, the figure shown represents a view in side elevation, and partly in section, of a water purification system constructed and arranged in accordance with the present invention.

50 This drawing illustrates the arrangement of a system having provision for utilizing the exhaust heat of an internal combustion engine for vaporizing the water in the boiler. Water is conducted from a suitable 55 source of supply into a feed water tank 2, having the overflow 3, and a gage device 4

connected with the float 5. This tank 2 communicates through a pipe 6 with a heater 7 of approved type, the coil 8 of which feeds into a boiler 9 through the pipe 60 10 provided with a valve 11 having the counterweighted operating arm 12. The pipe 6 leads directly into the base of the boiler where it is fitted with a valve 13, and said pipe 6 may also be provided with a 65 branch pipe connection 14 with the water jacket of the internal combustion engine 15.

The heater 7 is connected with the exhaust 16 of the engine, and the outlet 17 of the heater is led into the fire box 18 of the 70 boiler so that the exhaust gases of the engine are utilized first in the heater 7 and thereafter in the boiler to derive the full heating effect from said engine exhaust. The boiler is equipped with the usual water 75 gage 19.

From the boiler, the steam vapor is conducted by way of a pipe 20 to a condenser 21 of the atmospheric type (*i. e.*, depending upon the evaporative action of the atmosphere) arranged beneath a drip pipe 22. For further heating purposes a branch pipe 23 may be led through the stack 24 of the boiler, said pipe being fitted with a valve 25, and the pipe 20 being also provided with 85 a valve 26. The top of the condenser 21 comprises a shallow open basin for receiving the water dripping from the pipe 22 and provided with the lateral openings 70 for permitting the water to trickle out over the 90 opposite sides of the condenser, the waste water being collected by a drip pan 72 supported beneath the condenser and provided with the drain valve 74. The interior of the condenser 21 is provided with baffle 95 partitions 27 for forming a zigzag passage through the condenser chamber. Near the base of the condenser is connected an outlet pipe 28 having the valve 29 and trap bend portion 30. This outlet pipe leads into a 100 double-pipe condenser comprising an exterior casing 31 and cold water pipe 32 communicating with any convenient source of water supply. The exterior casing of this second condenser is in turn connected by a 105 pipe 33 with a reservoir 34 which is fitted with a sight gage 35, a pressure gage 36 and an outlet pipe 37, controlled by a valve 38, through which the water is drawn off for filling the ice cans.

110 Leading into the top of the condenser 21 is a pipe 39 communicating with a vacuum

casing 40 which is connected by a pipe 41 with a vacuum pump 42, a pressure gage 43 being mounted in connection with the pipe 41. The vacuum casing 40 is also provided 5 with pipe connections 44 and 45 to the opposite ends of the exterior casing 31 of the double-pipe condenser. A pipe 46 establishes connection between the intake end of 10 said condenser casing 31 and the condenser 21 just below the top baffle partition of the latter. A pipe 47 also connects the casing 40 and the reservoir 34, and said pipes 44, 45 and 47 are provided, respectively, with the valves 48, 49 and 50. The lower end of 15 the casing 40 is connected by a pipe 51 with the base of the boiler 9, and a branch pipe 52 connects pipe 51 with a float chamber 53 having the overflow pipe 54 and valve 55, as well as drain outlet valve 56. Near its upper 20 end this float chamber 53 communicates with the vacuum casing 40 through the tubular connection 57, and is provided with a float 58 having a stem portion 59 operating through a stuffing box 60 at the upper 25 chamber 53, the outer end of said stem portion being connected by a flexible cord 61 (passing over pulleys 62 and 63) with the valve arm 12 of the valve 11, whereby the latter is controlled in accordance 30 with the level of the water in chamber 53, and which, obviously, is the same as the boiler level by virtue of the connection through the pipe 51. The pipes 51 and 52 are equipped with the valves 64 and 65 respectively. 35

A partial vacuum is maintained in the casing 40 and its immediate connections by means of the pump 42. If the pressure in these connections is kept at approximately 40 6# gage pressure, the water will boil at approximately 170 degrees Fahr. Of course the pressure is the same at the water surface in the boiler as in the float chamber 53 and at the base of the vacuum casing 40 because 45 of the arrangement of pipe connections as described, whereby a reduction in the pressure is effected at both sides of the condensing apparatus. The water may be initially heated to bring it to approximate 50 boiling temperature by closing the valves 25, 26 and 64 and opening the valve 13, thereby causing the water to circulate through merely the boiler and heater; after which the valve 13 is closed and the other 55 valves opened. In operation it will be understood that the valves in the various vacuum connections are also opened. The reduced pressure through the condenser acts to draw the vapor from the boiler into the 60 condenser, and a part of the vapor is of course immediately condensed in the lower half of the condenser 21 and passes off through pipe 28. A portion of the vapor will be drawn off through the steam suction 65 line 46, while a smaller fraction, together

with some of the impure gases generated in the condensation process, will escape through pipe 39 into the vacuum chamber. Further condensation takes place in the double-pipe condenser, which feeds into the 70 reservoir by way of the pipe 33, during which process still further removal of the gaseous impurities is effected by the vacuum connections 44 and 45, and a final passage for the escape of such gases is provided by 75 means of the pipe 47. Thus from the boiler, where the first purification takes place and most of the impurities left behind, the influence of the vacuum action is maintained through all the course of the vapor throughout 80 the condensation process, and at every possible stage the gaseous impurities are withdrawn until the crystal pure product finally arrives and is stored in the reservoir ready for withdrawal through the pipe 37. 85 A constant water level is maintained in the boiler by the automatic action of the float 58, which opens or closes the valve 11 as may be required for this purpose. Hence, by connecting the vacuum side of the system 90 with the boiler by means of a water connection on the one hand and a vacuum communication on the other hand, a perfectly balanced system is obtained in which the water suppl^w is automatically maintained 95 constant and the steam vapor is produced with a lower heat consumption by virtue of the reduced boiler pressure, and the same vacuum action serves to remove any impure vapors generated throughout the course 100 of the condensation process.

It will thus be apparent that an effective and comparatively simple apparatus has been devised for carrying out the proposed objects of the invention, and while the foregoing represents what is now deemed to constitute the preferred form of embodiment of the invention, the right is reserved to such formal changes and modifications as may fairly fall within the scope of the appended claims. 110

Claims:

1. The process of purifying water which consists in distilling the water and removing the gaseous impurities from the vapor during condensation by subjecting said vapor to a continuous vacuum action at various points corresponding to the various successive stages of condensation of said vapor. 115

2. The process of purifying water which consists in boiling the water under reduced pressure and condensing the vapor arising from the water, and removing the gaseous impurities from said vapor during condensation by subjecting the vapor to a continuous vacuum action at various points corresponding to the various successive stages of condensation of said vapor. 120 125

3. A water purification system comprising, in combination, means for boiling the 130

- water, condensation apparatus arranged in communication with said boiling means, and vacuum producing means provided with connections with said apparatus at various 5 points corresponding to successive condensation stages throughout the course of said condensation.
4. A water purification system comprising, in combination, a boiler, condensation apparatus arranged in communication with said boiler, and vacuum producing means having connections providing communication both with said boiler and with different points of said condensation apparatus.
- 10 5. A water purification system comprising, in combination, a boiler, condensation apparatus arranged in communication with said boiler, and vacuum producing means having connections providing communication with said condensation apparatus and also with said boiler at points both above and below the normal water level therein.
- 15 6. A water purification system comprising, in combination, a boiler, condensation apparatus arranged in communication with said boiler, vacuum producing means hav-
- ing connections providing communication with said apparatus at various points corresponding to successive condensation stages, and means acting automatically to maintain 30 a constant water level in the boiler.
7. A water purification system comprising, in combination, a boiler, provided with a water admission valve, a float chamber and a condensation apparatus arranged in 35 communication with said boiler, said float chamber being operatively connected with said valve, and vacuum producing means having connections providing communication with said float chamber and condensation apparatus.
8. A water purification system comprising, in combination, a boiler, condensation apparatus arranged in communication with said boiler and provided with a storage 40 chamber, and vacuum producing means having connections providing communication both with said storage chamber and with different points of said condensation apparatus.

OLIVER M. CAMPBELL.
